GARRET TERPENING, OF JERSEY CITY, NEW JERSEY.

FIGURE TOY.

1,291,252.

Specification of Letters Patent.

Patented Jan. 14, 1919.

Application filed April 4, 1917. Serial No. 159,689.

To all whom it may concern:

Be it known that I, GARRET TERPENING, a citizen of the United States, and a resident of Jersey City, in the county of Hudson and State of New Jersey, have invented a certain new and useful Improvement in Figure Toys, of which the following is a full, clear, and exact specification.

This invention relates more particularly to a class of amusement devices.

My invention has for its object primarily to provide a toy made preferably in the form of a person representing a soldier with a gun which is adjustable for being raised and lowered to and from firing positions so as to interest and amuse children when at play, and which mainly consists of a figure with a chambered body having one or more passages leading into the chamber. The body is provided with flexible arms carrying a gun, and in the body is arranged manually operative mechanism for raising the gun so as to be disposed at intervals in positions as being aimed at an object.

Other objects of the invention are to provide spring actuated means for reversely operating the mechanism to lower the gun; and to provide a mechanical toy of a simple, efficient and durable construction which may be made in various sizes and shapes.

A practical embodiment of the invention is represented in the accompanying drawing forming a part of this specification in which similar characters of reference indicate corresponding parts in all the views, and will then be pointed out in the claims at the end of the description.

In the drawing, Figure 1 is a side elevation of one form of mechanical toy embodying my invention.

Fig. 2 is a longitudinal vertical section, partly in detail, taken through the toy.

Fig. 3 is an enlarged fragmentary sectional view, partly in detail, taken on the line III—III of Fig. 2, and

Fig. 4 is an enlarged perspective view, partly fragmentary, of the operating mechanism employed in the toy.

The device, or toy is preferably made in the form of a figure, as 10, representing a person such as a soldier having a body 11, head 12, arms 13, 14, and legs 15, 16 which

may be supported on a base 16^a. The figure 11 may be molded of metal, plastic material, or carved from wood by being formed of two halves which may be fastened together in any suitable manner, and the arms 13 and 14 of the figure may be of cloth, or otherwise made so as to be flexible for being swung upwardly and downwardly in a natural fashion. In the hands 17 and 18 of the arms of the figure is held a gun, or rifle, as 19, arranged so as to be raised to a firing position extending from the shoulder of the figure as well as being reversely moved.

In the body 11 of the figure 10 is a substantially rectangular chamber 20 extending from one of the hips of the figure to the shoulder thereabove, and in the back of the body is an elongated slot 21 which leads into the chamber. Communicating with the lower end of the chamber 20 is an elongated recess 22 which extends downwardly into the legs of the figure, and communicating with the upper end of the chamber may be a passage 23 extending upwardly in the head of the figure as well as outwardly through the back of the head. Also in one side of the body 11 is an elongated opening, as 24, leading into the chamber 20 and the upper end part of this opening is enlarged as well as terminating with an edge which is curved toward the front of the figure to provide a guide 24^a.

In order to permit the rifle to be raised to firing positions at intervals, I provide manually operative mechanism, as 25. The mechanism 25 has a block 26 which is somewhat the shape of a cube of a size so as to be moved freely upwardly and downwardly in the chamber 20 of the body 11, and on one face of the block is pivoted at 26^a a plate, or bar 27 protruding through the opening 24 so as to be slidably guided upwardly and downwardly in this opening with the movement of the block, and the upper end of this bar 27 is curved, as at 27^a. To the free end of this bar is screwed, or otherwise rigidly fastened the lower end, or butt of the rifle 19. Projecting laterally from another face of this block through the slot 21 is a plate, or handle 29 of a length so that its free end protrudes some distance beyond the back of

the body of the figure to allow the mechanism to be operated manually.

- Serving to yieldingly hold the block normally in the lower end of the chamber 20 of the body of the figure, to the central part of the lower end of the block is held the upper end of a spring, as 33, which is movably disposed downwardly in the recess 22 of the body, and the lower end of this spring 10 is held in the lower end of this recess. This spring also serves to cause a reverse action of the mechanism 25 when operated to raise the rifle to a firing position, as will be hereinafter more fully explained.
- 15 To permit the mechanism 24 to be manually operated independently of its operation by the handle 29 to the upper end of the block 26 may be fastened one end of a line, or cable 36 which is movably guided through
- 20 the passage 23 of the head of the figure as well as being guided over a pin 37 provided crosswise of the passage. The line 36 is of a length to extend some distance beyond the head of the figure, and on the free end of
- 25 this line may be a ring, as 38, to allow the line to be pulled.

When it is desired to operate the toy either the line 36 may be pulled downwardly, or the handle 29 of the mechanism 24 may be 30 forced upwardly in the slot 21 of the body of the figure. In either instance the block 26 of the mechanism will be guided upwardly in the chamber 20 of the body, and the bar 27 with the firing implement together with 35 the arms 13 and 14 of the figure will be likewise moved upwardly. When the block 26 is moved to the upper end of the opening 24 the curved end 27^a of the bar 27 will contact with the curved upper end or guide 24^a 40 of the opening 24, and this bar will be swung on the pivot 26^a for causing the rifle to be raised to a firing position, as indicated at 39 Fig. 1. When the line 36 and the handle 29 are released the tension of the spring 33 will 45 cause a reverse action of the mechanism 24 for lowering the rifle. In this manner a toy of a simple, durable and efficient form is provided for amusing children.

In the foregoing description, I have embodied the preferred form of my invention, 50 but I do not wish to be understood as limiting myself thereto, as I am aware that modifications may be made therein without departing from the principle, or sacrificing 55 any of the advantages of this invention, therefore I reserve to myself the right to make such changes as fairly fall within the scope thereof.

Having thus described my invention, I 60 claim as new and desire to secure by Letters Patent:—

1. A toy consisting of a figure with a chambered body and the upper end of said chamber being formed to provide a guide, a 65 block movable in the chamber, a gun having

its butt pivoted to the block, two flexible arm members attached to the body of the figure as well as being attached to the gun, means on the block, manually operable for moving the block to coact with the guide in 70 the chamber so that the gun will be raised and guided to firing positions, and a spring in the chamber for reversely moving the block to cause the gun to be lowered following the release of said operative means. 75

2. A toy consisting of a figure with a chambered body and the upper end of said chamber being formed to provide a guide, a gun, two flexible arm members attached to the body of the figure as well as being attached to the gun, a block movable in the chamber and the butt of the gun being pivoted to the block, said block being manually operable to coact with the guide in the chamber so that the gun will be raised and guided 80 to firing positions, and a spring in the chamber for reversely moving the block to cause the gun to be lowered following the release of said block. 85

3. A toy consisting of a figure with a chambered body and the upper end of said chamber being formed to provide a guide, a gun, two flexible arm members attached to the body of the figure as well as being attached to the gun, a block movable in the chamber and the butt of the gun being pivoted to the block, means on the block, manually operable for moving the block to coact with the guide in the chamber so that the gun will be raised and guided to firing positions, and a spring in the chamber for reversely moving the block to cause the gun to be lowered following the release of said block. 95

4. A toy consisting of a figure with a chambered body, a gun, two flexible arm members attached to the body of the figure as well as being attached to the gun, and spring actuated means in the chamber and the butt of the gun being pivoted to the means, said means being manually operable so that the gun will be raised and guided to 100 firing positions. 110

5. A toy consisting of a figure with a chambered body, a gun, two flexible arm members attached to the body of the figure as well as being attached to the gun, mechanism in the chamber and the butt of the gun being pivoted to the mechanism, said mechanism being manually operable so that the gun will be raised and guided to firing positions, and a spring in the chamber for reversely operating the mechanism to cause the gun to be lowered following the release of said operative mechanism. 115 120

6. A toy consisting of a figure with a chambered body and the upper end of said chamber being formed to provide a guide, movable means in the chamber, a gun having its butt pivoted to the movable means, two 130

flexible arm members attached to the body of the figure as well as being attached to the gun, a handle on the movable means, manually operable for moving the block to coact with the guide in the chamber so that the gun will be raised and guided to firing positions, and a spring in the chamber for reversely moving the movable means to cause

the gun to be lowered following the release of said handle.
